UNITED STATES PATENT OFFICE

2,012,326

AUTOMATIC TALKING MACHINE

Harry Archibald Thompsett, London, England,
assignor, by mesne assignments, to Radio Cor-
poration of America, New York, N. Y., a corpo-
ration of Delaware

Application December 4, 1930, Serial No. 499,999
In Great Britain December 16, 1929

7 Claims. (Cl. 179—100.4)

This invention relates to improvements in automatic talking machines and in particular to automatic talking machines of the kind operating with an electrical reproducer or pick-up. With machines of this kind, there are periods of time between the completion of one reproduction and the commencement of the next when the needle of the reproducer is in engagement with a part of the surface of the rotating record in the playing position which does not contain the sound record groove. For example, at the end of the automatically effected repositioning movement of the reproducer, the needle may be engaged with the part of the surface of the record outside the commencing groove preparatory to being fed inwardly to commence reproduction of a selection.

With machines of this kind, as hitherto known, the engagement of the needle or stylus of an electrical reproducer with parts of the moving record outside the sound record groove gives rise to unpleasant noises which are due to movements imparted to the stylus as it slides over the record surface, these movements being converted into electrical oscillations which are amplified and transmitted to the loudspeaker.

Furthermore, there is the possibility of other noises being produced in the loudspeaker during the carrying out of automatic operations apart from those referred to above, due to the engagement of the stylus with the record surface.

The object of the present invention is to provide a machine in which the occurrence of these unpleasant noises is avoided.

According to the invention, means are provided whereby the electrical circuit of the electrical reproducer or pick-up is short circuited as soon as a series of automatic operations is commenced, the short circuited condition being maintained until the needle is in engagement with the commencing sound line of the record to be played. Instead of the pick-up leads being short circuited, the object of the invention may be achieved by short circuiting the amplifier or even the loudspeaker itself. The invention is readily applicable to a machine of the kind described in my Patent No. 1,879,593 in which the motor of the machine is coupled at intervals to a cam shaft through which all the automatic operations of the machine, including the ejection of the played record, the feeding of a new record to the playing position and the repositioning of the reproducer, are effected.

The invention is also applicable to other types of automatic machine such as those which are adapted to repeatedly play a single record.

The invention is illustrated, by way of exam-

ple, in the accompanying drawing as applied to an automatic talking machine of the kind adapted to play a series of records fed singly or in succession to the turntable from a magazine as described in my above referred to patent and using an electrical pick-up.

Fig. 1 illustrates the short circuiting device according to the invention in plan view.

Fig. 2 is a view in elevation corresponding to Fig. 1.

Fig. 3 is the circuit diagram.

In the machine according to my above-identified patent, a cycle of automatic operations including the raising, swinging and lowering of the sound arm, feeding of records from the magazine to the turntable and ejection of played records are effected during one complete revolution of a cam shaft which is held stationary during playing of a record but is coupled to the machine motor, so as to be rotated thereby to make one complete revolution, by a clutch device operable by a reversal of the direction of movement of the sound arm when the stylus reaches the end of a record.

In the drawing, Fig. 1 represents the cam shaft carrying a gear wheel 2, Fig. 2, through which it is rotated at intervals by the machine motor, not shown.

The cam shaft 1 is mounted for rotation in a bearing sleeve 3 carried on a base plate 4, and beneath this base plate 4, in a suitable position, is carried a bracket 5. The bracket 5 serves to support an electric switch formed by two spring blades 6, 7 insulated from one another and from the base plate 4 by blocks 8 of insulating material. The blades 6 and 7 are connected electrically, one to each of the leads connecting the pick-up, represented diagrammatically by 9 in Fig. 3, to the amplifier 10.

The blades 6, 7 are provided on adjacent faces and near their free ends with suitable contact points 11, 12 and the arrangement is such that the blades 6, 7 tend to contact with one another to bring the points 11, 12 together to thereby short circuit the pick-up. The free end of the blade 6 is provided with a curved extension 13.

On one of the cams 14 fast on shaft 1 is fixed a button 15 of insulating material, and the position of this button 15 on cam 14 is such that, during playing of a record, the button 15 is held stationary in the position shown in Fig. 1 where it engages the extension 13 of blade 6, so that the latter is deflected and the switch is held open.

As soon as rotation of the cam shaft 1 commences in the direction indicated by the arrow in Fig. 1 to effect the automatic cycle of move-

ments in known manner, the button 15 moves from engagement with extension 13 of blade 11 and the contacts 11, 12 move together to short circuit the pick-up 9.

5 When the complete revolution of the cam shaft 1 has been made and the cycle of automatic operations has been completed, the button 15 returns to the position indicated in Fig. 1. The coupling between the motor and cam shaft 10 is now broken in known manner so that the cam 14 is brought to a standstill in a position where the switch 6, 7 is open.

The position of the insulated button 15 on the cam 14 and the timing of the movements of the cam shaft 1 and the reproducer moving means, not shown, may be so selected and determined that the stylus of the reproducer or pick-up 9 contacts with the record to be played and moves into engagement with the first sound record groove before the short circuiting switch 6, 7 is opened, so that the amplifier and loud-speaker remain uninfluenced by the pick-up until the required moment.

I claim:

25 1. The method of controlling an automatic phonograph of the type including an electrical reproducing instrumentality in circuit with an audio amplifier and adapted to successively reproduce a plurality of records in cycle by means 30 of said instrumentality which comprises short-circuiting said instrumentality during at least a portion of the non-playing part of the cycle whereby to prevent any output signals from said instrumentality from reaching said amplifier during said portion.

40 2. The method of controlling an automatic phonograph of the type adapted to successively reproduce a plurality of records electrically by means of an electrical reproducer in circuit with an audio amplifier and to perform a cycle of 45 automatic operations between succeeding records which comprises short-circuiting the electrical reproducer thereof as soon as the cycle of operations is commenced upon completion of each individual record to prevent any reproducer output signals from reaching said amplifier, and maintaining said reproducer in short-circuited condition until the reproducer is in engagement with the sound track of the succeeding record.

50 3. In a phonograph of the type wherein sound is reproduced from a record having a recorded portion and an unrecorded portion, the combination of an electrical translating device adapted to be energized by either of said portions, an 55 audio amplifier in circuit with said device, switch means connected across said device in advance of said amplifier for controlling the operating condition of said device, and means for maintaining said switch means closed, whereby to short-circuit said device, during the time that said device is not in contact with said recorded portion.

60 4. In an automatic phonograph of the type adapted to carry out a cycle of automatic oper-

ations and wherein sound is reproduced from records having a recorded portion and an unrecorded portion, the combination of an electrical sound reproducing device adapted to be energized by either of said record portions, an audio amplifier in circuit with said device, a switch connected across the output of said device in advance of said amplifier for controlling the operating condition thereof, means for maintaining said switch open while said device is in engagement with the recorded portion of a record, whereby to render said device operative to reproduce sound, and means whereby said switch is maintained closed after said device is in engagement with the unrecorded portion of the record 15 and for the balance of the cycle, whereby to render said device inoperative to reproduce sound.

5. In an automatic phonograph of the type adapted to carry out a cycle of automatic operations and wherein sound is reproduced from records having a recorded portion and an unrecorded portion including a control groove at the end of the sound groove for controlling the operating cycle of the phonograph, the combination of an electrical sound reproducing device adapted 25 to be energized by either of said record portions, an audio amplifier in circuit with said device, a switch connected across the output of said device in advance of said amplifier for controlling the operating condition thereof, means for maintaining said switch open while said device is in engagement with the recorded portion of a record, whereby to render said device operative to reproduce sound, and means whereby said switch is maintained closed during the balance of the 30 cycle after said device has engaged said control groove and a series of automatic operations has been initiated, whereby to render said device inoperative to reproduce sound during said balance of the cycle.

40 6. In a phonograph, an electrical translating device, a switch connected across the output of said device, said switch including a pair of spring members constantly tending to contact each other, said spring members causing said device 45 to be short circuited when in contact with each other, a rotatable shaft, means fixed to and rotatable with said shaft, and a switch engaging member on said means adapted to be moved into engagement with one of said spring members as 50 said shaft rotates whereby to maintain said spring members separated.

7. In a phonograph, an electrical translating device, a switch connected across the output of said device and adapted, when closed, to short-circuit said device, a rotatable shaft, a member fixed to and rotatable with said shaft, said member including a switch controlling element, and said switch including a pair of spring blades one of which is located in the path of movement of 55 said element, whereby said element is adapted to engage one of said spring blades in response to rotation of said shaft.

HARRY ARCHIBALD THOMPSETT.
